GASEOUS ELECTRIC DISCHARGE DEVICE

Eduard G. Dorgelo, Eindhoven, Netherlands, assignor to General Electric Company, a corporation of New York

Application April 6, 1934, Serial No. 719,251
In the Netherlands April 22, 1933

4 Claims. (Cl. 176—1)

The present invention relates to gaseous electric discharge devices generally and more particularly the invention relates to such devices useful as light sources and as ultra-violet generators.

The object of the invention is to provide a gaseous electric discharge device of simple structure useful as a light source and as an ultra-violet generator. Another object of the invention is to provide a gaseous electric discharge lamp the emitted light of which is a mixture of light from an incandescent body and an electric discharge. A further object of the invention is to provide such a device the manufacturing cost of which is reduced to a minimum. Still further objects and advantages attaching to the device and to its use and operation will be apparent to those skilled in the art from the following particular description.

In accordance with these objects the new and novel gaseous electric discharge device comprises a container having a gaseous atmosphere therein. Said container has mounted therein two resistances connected in series and a thermionic, filamentary cathode provided with electron emitting material, which cathode is connected in series with said resistances and mounted between said resistances. When the cathode is of the type having a heating element this element is connected in series with said resistances. When the device is connected to a source of alternating current a potential difference is created between the cathode located in the center of this series connection and the ends of the resistances that are not connected to this cathode. Each of these ends has alternately, a positive and a negative potential with respect to the cathode. A discharge then takes place between the cathode and that end of the resistance which, at that particular instant, has a positive potential with respect to the cathode, while the other resistance serves as a series impedance for the discharge. In the subsequent half-cycle of the alternating current, the functions of the two resistances are reversed. The resistances serve, consequently, both as series impedances and for the formation of the voltage difference which is necessary for the discharge.

If the magnitude of the resistance which is required for the production of a favorable discharge voltage differs from the value which is most suitable for the stabilization of the discharge current, it is possible to connect between the two resistances two electrodes or two heat-

ing elements, in which case a third resistance is connected between these two glow electrodes or heating elements. As will be explained in greater detail later herein this third resistance coacts in the production of the voltage for the discharge but does not constitute a part of the series resistance which is connected in series with the discharge.

The resistances are preferably selected of such a size that they become incandescent during operation and emit light. These light rays then mix with the rays produced by the discharge. When the discharge device is used as an ultra-violet generator the container 1 is made of a material which transmits ultra-violet rays, such as quartz.

When desired, those ends of the resistances which function as anodes have a special shape in order to make these ends better suited to carry the discharge current. The ends are made thicker or provided with a special small metal plate, for example.

The construction of the discharge device according to the invention is very simple, especially because of the fact that only two current-supply wires need to be brought out through the stem. The discharge device is provided with the usual 2-pole base, such as an Edison base or a Swan base, and is connected directly to a current source. It is not necessary to use special stabilization impedances external to the container of the device.

In the drawing accompanying and forming part of this specification several embodiments of the invention are shown in which

Fig. 1 is a schematic view of a gaseous electric discharge device embodying the present invention,

Fig. 2 is a wiring diagram of another embodiment of the invention, and

Fig. 3 is a wiring diagram of another embodiment of the invention.

It will be understood that the embodiments of the invention illustrated in Figs. 2 and 3 of the drawing are useful in the type of discharge device illustrated in Fig. 1.

The discharge device shown in Fig. 1 has a bulb 1 to which a stem tube 2 has been sealed. This stem tube 2 carries a glass stem 3 to which two metal supporting wires 4 are fastened. Two supporting wires 5 and 6 are sealed into the stem tube 2. Between these supporting wires 5 and 6 and the ends of the supporting wires 4, two resistance wires 7 and 8, which consist of tungsten, for example, are fastened, while between the two

supporting wires 4 a cathode 9 is mounted. Said cathode 9 consists of a nickel filament wrapped around a tungsten filament and a coating of material of high electron emissivity characteristics, 5 for example, barium oxide. The resistances 7 and 8 and the cathode 9 are connected in series, while the supporting wires 5 and 6 constitute the continuation of the resistances 7 and 8 but are considerably stronger than the latter. The supporting wires 5 and 6 are connected to the current-supply wires 10 and 11.

The discharge device has a gas filling therein, consisting of a mixture of a rare, starting gas, such as neon at a few mm. pressure, and a metal 15 vapor, such as mercury vapor.

When the discharge device is connected to an alternating current source, the current flowing through the resistances 7 and 8 and the cathode 9 produces a potential difference between the supporting wires 5 and 6 and the cathode 9. In the case of a sufficient electron emission by the cathode, a discharge takes place during every alternating-current half cycle between the cathode 9 and the supporting wire which has a positive potential with respect to the cathode 9. The discharge takes place, for instance, between the supporting wire 5 and the cathode 9. The discharge current flows then through the resistance 8 which serves as the stabilizing resistance for the discharge. In the next half cycle the discharge takes place between the glow cathode 9 and the supporting wire 6, while the resistance 7 in that case serves as the series resistance. The resistances 7 and 8 are of such 35 size that they become incandescent during the operation of the device and emit light. This light is mixed with the light produced by the discharge.

In order to take the resistances 7 and 8 out of the discharge path the ends of the supporting 40 wires 4 are bent to the rear so that the resistances 7 and 8 do not lie in the plane of the supporting wires 5 and 6.

The cathode 9 is of the indirectly heated type, when desired. The heating element of this type 45 of cathode is connected to the supporting wires 4. The heating element of the cathode is surrounded by a small metal cylinder which is covered with a substance of high electron emissivity characteristics, such as barium oxide, and which is 50 electrically connected to a point on the heating element. This embodiment is shown in Fig. 2 of the drawing in which 12 indicates the indirectly heated cathode.

In the constructions according to Figs. 1 and 2, 55 the resistances 7 and 8 serve both for the production of the necessary voltage difference for the discharge and also for limiting the discharge current. If the requirements which are placed on the resistances by this double function, can-60 not be made to agree, the arrangement shown schematically in Fig. 3 is used. In this case two thermionic cathodes 13 and 14 similar to the cathode 9 of Fig. 1, and a resistance 15 connected between these cathodes 13 and 14, are connected 65 in series with, and placed between the resistances 7 and 8. The discharge takes place between the cathode 13 and the supporting wires 6, while the resistance 7 serves as the series impedance, or the

discharge takes place between the cathode 14 and the supporting wire 5, in which case the resistance 8 functions as the series resistance. The voltage difference between the cathode 13 and the wire 6 or between the cathode 14 and the wire 5 is brought about by the resistances 8 and 15 connected in series and the cathode 14, or by the resistances 7 and 15 and the cathode 13. The resistance 15 consequently coacts in the production of the discharge voltage but does not contribute to the limitation of the discharge current; this is accomplished by the resistances 7 and 8. The resistances 7 and 8 in this embodiment are dimensioned in such a way that they effect a good stabilization while independently thereof the magnitude of the resistance 15 is selected in such a way that a voltage difference favorable for the discharge is produced thereby.

While I have shown and described and have pointed out in the annexed claims certain novel 20 features of the invention, it will be understood that various omissions, substitutions and changes in the forms and details of the device illustrated and in its use and operation may be made by those skilled in the art without departing from 25 the broad spirit and scope of the invention.

What I claim as new and desire to secure by Letters Patent of the United States is:—

1. A gaseous electric discharge device comprising a container, a gaseous atmosphere therein, 30 two resistances, a current lead for each of said resistances and a thermionic cathode sealed therein, said resistances being connected in series across said current leads and said cathode being connected in series with said resistances, said 35 cathode being mounted between said resistances, said current leads serving as anodes for said cathode.

2. A gaseous electric discharge device comprising a container, a gaseous atmosphere therein, 40 two resistances, a current lead for each of said resistances and a thermionic cathode sealed therein, said resistances being connected in series across said current leads and said cathode being connected in series with said resistances, said 45 cathode being mounted between said resistances, said current leads serving as anodes for said cathode, said resistances being heated to incandescence by the operating current of said device.

3. A gaseous electric discharge device comprising a container, a gaseous atmosphere therein, three resistances, two current leads and two thermionic cathodes sealed therein, said resistances and said cathodes being connected in series across said current leads, each of said cathodes being 55 mounted between a pair of said resistances, said current leads serving as anodes for said cathodes.

4. A gaseous electric discharge device comprising a container, a gaseous atmosphere therein, three resistances across said current leads and 60 two thermionic cathodes sealed therein, said resistances and said cathodes being connected in series, each of said cathodes being mounted between a pair of said resistances, said current leads serving as anodes for said cathodes, said 65 resistances being heated to incandescence by the operating current of said device.

EDUARD G. DORGELO.
